H. M. KREH.
HUMIDOR CIGAR BOX.
APPLICATION FILED MAY 9, 1913.

1,087,022.

Patented Feb. 10, 1914.

UNITED STATES PATENT OFFICE.

HENRY M. KREH, OF PHILADELPHIA, PENNSYLVANIA.

HUMIDOR CIGAR-BOX.

1,087,022.

Specification of Letters Patent. Patented Feb. 10, 1914.

Application filed May 9, 1913. Serial No. 766,593.

To all whom it may concern:

Be it known that I, HENRY M. KREH, a citizen of the United States, residing in Philadelphia, Pennsylvania, have invented 5 certain Improvements in Humidor Cigar-Boxes, of which the following is a specification.

My invention relates to containers or receptacles for tobacco products, more particularly cigars, and the object of my invention is to provide an "original package" container with means for keeping cigars in a properly damp or moist condition. By preference, my improved means are removable 10 from the box as may be desired; one part of the same consisting of a pad which will require moistening at intervals.

My improved construction comprises a foraminous wall or partition which may be 20 removably mounted in the box adjacent to or contacting with the tobacco products carried therein; such partition forming between it and one wall of the container an air space and a compartment for the reception of a moistening pad.

These and other features of my invention will be more fully described hereinafter, reference being had to the accompanying drawings forming part thereof, in which:

30 Figure 1, is a perspective view of a cigar box equipped with the moistening device forming the subject of my invention; Fig. 2, is a cross sectional view on the line 2—2, Fig. 1; Fig. 3, is a plan view of one corner 25 of the box shown in Fig. 1; Fig. 4, is a perspective view of the foraminous partition and pad shown in Figs. 1 and 2, and Figs. 5, 6 and 7, are views illustrating modifications within the scope of my invention.

40 In the drawings, 1 represents an original package receptacle or container for cigars, which may be of wood having the usual cover, and in all respects the same as an ordinary wooden cigar box. For the purpose 45 of my invention, the box may be made slightly wider than usual. Within this box, I place a foraminous partition 3, which may be at front or rear of the box, and may be engaged therewith in any suitable manner 50 that will insure spacing of the same from one wall so as to provide an air space or compartment 4 for the reception of a moistening pad 5; the latter being so disposed therein as to avoid all danger of direct contact 55 with the cigars.

As shown in Figs. 1, 2 and 3, the forami-

nous wall 3 is in the shape of a sheet of perforated metal with projecting ends 6 adapted to grooves 7 in the side walls 8 of the cigar box, as clearly shown. When this 60 partition is dropped into place, it forms an air space and room for the reception of the moistening pad 5, which may be made of any suitable porous material, preferably backed by a sheet 9 of substantially non-porous material, metal or the like, to make it sufficiently stiff as to be easily removed from the box when it is desired to moisten the same. It may be otherwise stiffened if desired. The foraminous partition, however, 70 may be combined with the box in various ways, and in Figs. 5, 6 and 7, I have shown other ways of accomplishing the same result. In Fig. 5, for instance, which view is similar to Fig. 3, the foraminous partition 75 is a single sheet of metal adapted to grooves 7^a formed in the ends of the box, and the support 9^a for the pad has projecting upper and lower walls 10 to space it from the foraminous partition. As shown in Fig. 6, 80 the foraminous plate is turned back on itself at 11 so as to be spaced from the front wall of the cigar box, or it may be caught between the end of the front wall at its point of engagement with the side wall by continuing the bend at right angles to the partition, as shown in Fig. 6, or by turning it in the manner indicated at 12 in Fig. 7. It will be understood further that the foraminous 85 plate forming the compartment with the moistening pad may be at the front or rear of the box as desired, and that in some instances it may be at both front and rear of the box.

The construction in Figs. 1, 2 and 3, is 90 preferred to a certain extent, inasmuch as the bending over of the foraminous plate at 13 stiffens the same and permits its ready introduction into or removal from the box, and further, because such turning or bending of the edges of the sheet provides the desired space to receive the moistening pad, which is thereby confined against movement. Any means of insuring an air space, however, with room for the moistening pad, so 95 that the latter will not contact with the foraminous plate at the portion adjacent to the cigars may be employed, without departing from my invention.

I claim:

1. A humidor adapted for use with an original box of cigars, said humidor consist-

110

ing of a perforated plate fashioned with flanges forming an air space at one side, said plate having flanges at its ends adapted to edgewise fit in kerfs or grooves made vertically in the ends of the box, and a separate plate insertible edgewise through the open top of the box and having a moistening pad parallel with and separated from the perforated plate, said second plate adapted to fit within the space between the perforated plate and the adjacent wall of the box.

2. A humidor adapted for use with an original box of cigars, said humidor consisting of a perforated plate having its longitudinal edges bent to one side and having flanges at its ends extending beyond said bent over portions and adapted to be in-

serted edgewise into kerfs or grooves made vertically in opposite walls of the box, the turned-over edges of said plate forming an air space, and a separate plate insertible edgewise through the open top of the box and into the space between the turned-over edges of the first named plate and the contiguous wall of the box, and having a moistening pad arranged substantially parallel with the first-named plate.

In testimony whereof, I have signed my name to this specification, in the presence of two subscribing witnesses.

HENRY M. KREH.
